UNITED STATES PATENT OFFICE

CLARENCE LIPPER, OF PHILADELPHIA, PENNSYLVANIA, ASSIGNOR TO LIPPER MANUFACTURING CO., A CORPORATION OF PENNSYLVANIA

TEXTILE FABRIC

Application filed November 30, 1929. Serial No. 410,835.

My invention relates to a new and useful textile fabric of the type generally known as braid and more particularly hat braid, that is, a narrow braid-like textile fabric adapted for use in making hats or adapted to be made into hats. My invention relates to "hat braiding" of the general type disclosed in and forming the subject matter of the Lipper Patent No. 1,618,763, of February 22, 1927, and my present invention may be considered, in part, that is, in some of its embodiments, to be an improvement upon the hat braid forming the subject matter of said Lipper Patent No. 1,618,763.

My invention relates more particularly to a narrow textile fabric or braid, including certain so-called fillers consisting of still narrower flat ribbon-like strands which will retain their shape when embodied into the finished fabric.

My invention consists in first forming any suitable grade or quality of hemp or similar material into relatively narrow, flat ribbon-like strips or strands, by braiding (on any suitable braiding machine). Two or more of the narrow, flat, ribbon-like braided hemp strands are then extended longitudinally of the ultimately desired fabric or hat braid, and are encased or united in such a manner as to form a single, unitary, narrow textile fabric, to wit, a hat braid, of a width somewhat greater than the aggregate width of the two or more narrower strips or strands of braided hemp.

My invention further consists of other novel details of construction in a narrow fabric or hat braid, forming the subject matter of the instant invention, which will be described more fully hereinafter and referred to in the appended claims.

For the purpose of illustrating my invention I have shown forms thereof which are at present preferred by me, since they will give in practice satisfactory and reliable results, although it is to be understood that the

various instrumentalities of which my invention consists can be variously arranged and organized and that my invention is not limited to the precise arrangement and organization of the instrumentalities as herein shown and described. 50

Referring to the drawings in which like reference characters indicate like parts,

Figure 1 represents a plan view of the face of a short piece of my novel textile fabric, 55 shown approximately actual size.

Figure 2 represents a similar plan view showing the back of my novel fabric.

Figure 3 represents a much enlarged view of the face of the fabric, similar to that shown 60 in Figure 1, with some of the fabric structure removed, so as to expose to view the filler strands of braided hemp.

Figure 4 represents a similar enlarged view of the back of my novel fabric. 65

Figure 5 represents a section on line 5—5 of Figure 3.

Figure 6 represents a much enlarged and somewhat diagrammatical view of the facing strands of the novel fabric illustrated in 70 Figures 1 to 5 inclusive.

Figure 7 represents a plan view of the face of a piece of textile fabric embodying a modified form of my present invention, shown 75 approximately actual size.

Figure 8 represents a similar plan view of the back of the novel textile fabric of this modified embodiment.

Figure 9 represents a plan view of the face of the fabric, as shown in Figure 7, on a 80 much enlarged scale.

Figure 10 represents a plan view of the back of the fabric, as shown in Figure 8 on a similarly enlarged scale.

Figure 11 represents a section on line 85 11—11 of Figure 10.

In carrying out this invention, narrow, flat, ribbon-like strips or strands 12 and 13 are formed by braiding hemp of any suitable quality or grade, or similar relatively stiff 90

material. The narrow, ribbon-like braided hemp strands 12 and 13 are then arranged warp-wise on suitable flat warp knitting machines, of the general character illustrated and referred to in the Patent No. 1,618,763, herein above mentioned.

A series of parallel chains of knitted stitches 14, 15 and 16 are then formed of corresponding warp threads on said knitting machine, parallel to said braided hemp strands and disposed adjacent the edges thereof as indicated in Figures 1 to 5 inclusive. The longitudinally disposed chains of knitted stitches 14, 15 and 16 are preferably 10 formed of artificial or synthetic cellulose threads, such as the so-called visca threads, or so-called artificial straw threads.

With the formation of these successive stitches or links of the longitudinal or warp 20 chains 14, 15 and 16, transverse or weft-like threads or strands 17 and 18 are extended back and forth across the width of the fabric on the back and on the face thereof, respectively, and are interlaced with the successive 25 stitches or links of the series of longitudinal or warp-like knitted chains 14, 15 and 16, thereby to tie together the series of knitted chains 14, 15 and 16, and the braided hemp filler strips 12 and 13 disposed therebetween.

30 The back weft threads 17 may be any suitable, relatively stiff material, as for instance plain visca or artificial straw threads. The face weft strands 18 on the other hand are of a composite nature illustrated on a much 35 enlarged scale in Figure 6. Thus the face weft strands are of the general character disclosed in the Lipper Patent No. 1,661,142, of February 28, 1928, comprising a taut core strand 19 of cotton or the like, relatively stiff 40 and ribbon-like body strands 20 of artificial cellulose, such as artificial straw, wrapped loosely around said core strand 19 in a generally spiral formation and a relatively thin binder strand 21 wrapped more tightly 45 around said core strand and said body strands 19 and 20 respectively to bind the latter to the former at intervals. The composite strand 18 thus formed is of a generally loose, bulky and crinkled character, and when interlaced with the knitted chains 14, 15 and 16, serves the dual function of a surfacing 50 material in relation to the braided hemp filler strands 12 and 13, and as a spacing means for said knitted chains 14, 15 and 16, since the generally rough or crinkled character of the weft strand 18 causes an interlocking between said crinkled weft thread 18 and the series of knitted chains 14, 15 and 16, which prevents the latter from slipping to and fro 55 upon the wefts 17 and 18 and from varying its spaced relation. This latter function of the surface weft strands 18 is like the function of the crinkled weft threads in the textile fabric of the Lipper Patent No. 1,618,763.

60 65 The straight visca or artificial straw weft

threads 17 on the back of the instant novel fabric, in turn serve to impart transverse rigidity or stiffness to the fabric, since these transverse weft threads 17 are relatively stiff or rigid and extend substantially straight across the fabric. If desired, the straight and plain weft threads 17 may also be extended across the face of the fabric, in addition to, or supplemental to, the composite face weft threads 18. The use of the stiffening weft threads 17 on the face of the fabric as well as on the back, serves to impart added transverse rigidity to the finished narrow fabric or braid.

In Figures 7 to 11 inclusive, another embodiment of the instant invention is illustrated, in which, like in the embodiment illustrated in Figures 1 to 6 inclusive, a plurality of parallel braided hemp or filler strands 23, 24 and 25 are extended through the fabric longitudinally by feeding the braided hemp strands through the knitting machine warp-wise. In this particular embodiment of the invention however, instead of uniting the series of parallel longitudinal braided hemp strands 23, 24, and 25, into the single unitary narrow fabric, by means of a series of non-interlacing rows of warp-wise knitted chain stitches and separate weft threads extended transversely of the fabric and interlaced with the separate rows of chain stitches;—the braided hemp strands are here united into a unitary fabric structure merely by a series of generally warp-wise or longitudinally knitted chain stitches of an interlacing character. Thus, in this particular embodiment of the invention no distinct weft threads are employed to unite the braided hemp strands or to encase the same, but instead, the successive rows of warp-wise knitted chain stitches interlace with each other on the face and on the back of the finished fabric, so as to encase the braided hemp strands.

Thus, in forming this modified narrow fabric according to this invention, the warp threads of which the chains 26, 27, 28 and 29 are formed, are shifted back and forth between adjacent needles of the knitting machine, on the face and on the back of the hemp strands 23, 24 and 25, so as to cause the rows of knitted chain stitches to interlace with each other on the face and on the back of the finished fabric, by means of the connecting links 30. By this means the plurality of braided hemp strands 23, 24 and 25 are likewise united into a single unitary fabric of the narrow type usually referred to as hat braid.

According to the present invention a narrow fabric or hat braid is formed of a plurality of narrower ribbon-like braided hemp strands united into a single unitary fabric structure by means of an exterior casing formed either of a combination of non-interlacing rows of warp-wise knitted chain stitches and weft threads interlaced there-

with, or a series of interlacing rows of knitted stitches extending longitudinally of the fabric and connected by interlacing links. In either embodiment of the invention a highly desirable and serviceable hat braid is formed, which may either present the appearance of the individual braided hemp strands 23, 24 and 25, or the surface thereof may be formed of a casing which entirely conceals the hemp strands, as for instance in the first modification illustrated. In either event a comparatively rigid and stiff, narrow fabric or hat braid is formed which readily adapts itself to the formation of hats by the conventional methods commonly employed.

I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I claim as new and desire to secure by Letters Patent, is:—

1. Hat braid comprising a plurality of longitudinal flat, ribbon-like braided strands of a relatively stiff material, united into a single unitary fabric by means of an exterior casing including rows of knitted stitches extending along the edges of said flat, ribbon-like braided strands.

2. Hat braid comprising a plurality of longitudinal flat, ribbon-like braided hemp strands, united into a single unitary fabric by means of an exterior casing including rows of knitted stitches extending along the edges of said flat, ribbon-like braided strands.

3. Hat braid comprising a plurality of longitudinal flat, ribbon-like braided strands of a relatively stiff material, united into a single unitary fabric by means of an exterior casing including rows of knitted stitches extending along the edges of said flat, ribbon-like braided strands, and threads interconnecting said rows of knitted stitches on the face and on the back of the fabric.

4. Hat braid comprising a plurality of longitudinal flat, ribbon-like braided hemp strands, united into a single unitary fabric by means of an exterior casing including rows of knitted stitches extending along the edges of said flat, ribbon-like braided strands, and threads interconnecting said rows of knitted stitches on the face and on the back of the fabric.

5. Hat braid comprising a plurality of longitudinally extending, relatively flat, ribbon-like, braided strands of a relatively stiff material, a series of non-interlacing longitudinal rows of knitted stitches of suitable thread adjacent the edges of said braided strands, and transversely extending weft threads inter-

laced with the successive stitches of said longitudinal rows of knitted stitches, on the face and on the back of said braided strands, connecting said rows of knitted stitches and said braided strands intermediate thereof, into a single unitary fabric.

6. Hat braid comprising a plurality of longitudinally extending, relatively flat, ribbon-like, braided hemp strands, a series of non-interlacing longitudinal rows of knitted stitches of suitable thread adjacent the edges of said braided strands, and transversely extending weft threads interlaced with the successive stitches of said longitudinal rows of knitted stitches, on the face and on the back of said braided strands, connecting said rows of knitted stitches and said braided strands intermediate thereof, into a single unitary fabric.

7. Hat braid comprising a plurality of longitudinally extending, relatively flat, ribbon-like, hemp strands, a series of non-interlacing longitudinal rows of knitted stitches of suitable thread adjacent the edges of said hemp strands, and transversely extending weft threads interlaced with the successive stitches of said longitudinal rows of knitted stitches, on the face and on the back of said hemp strands, connecting said rows of knitted stitches and said hemp strands intermediate thereof, into a single unitary fabric.

8. Hat braid comprising a plurality of longitudinally extending, relatively flat, ribbon-like, hemp strands, united into a single unitary fabric structure by means of rows of knitted stitches extending longitudinally along the edges of said hemp strands, and threads on the face and on the back of said hemp strands interconnecting said rows of knitted stitches.

9. Hat braid comprising a plurality of longitudinally extending, relatively flat, ribbon-like, hemp strands united into a single unitary fabric structure by means of a series of non-interlacing rows of knitted chain stitches extending longitudinally along the edges of said hemp strands and artificial cellulose weft threads on the face and on the back of said hemp strands interlaced with the stitches of said series of rows of knitted chain stitches.

10. Hat braid comprising a plurality of longitudinally extending flat, ribbon-like, hemp strands united into a single unitary fabric structure by means of a series of non-interlacing rows of knitted chain stitches extending longitudinally along the edges of said hemp strands and weft threads on the face and on the back of said hemp strands interlaced with the stitches of said series of rows of knitted chain stitches; some of said weft threads being relatively bulky and crinkled composite strands including a core thread and a flat, ribbon-like artificial cel-

lulose thread loosely wrapped around said core thread in a generally spiral formation.

11. Hat braid comprising a plurality of longitudinally extending flat, ribbon-like, braided hemp strands knitted into a single unitary fabric structure by means of a series of non-interlacing rows of knitted chain stitches extending longitudinally along the edges of said hemp strands and weft threads 5 on the face and on the back of said hemp strands interlaced with the stitches of said series of rows of knitted chain stitches; some of said weft threads being relatively bulky and crinkled.

10 12. A millinery and trimming fabric including a plurality of parallel, longitudinal, braided hemp strands united into a unitary fabric structure by transverse threads knitted thereonto including synthetic cellulose. 70

15 In witness whereof I have hereunto set my hand this 21st day of March, 1929.

16 CLARENCE LIPPER. 75

17 13. A millinery and trimming braid including a longitudinal braided core strand of 20 a relatively form-retaining material and transverse threads knitted onto said longitudinal braided core. 80

18 14. A millinery and trimming braid including a longitudinal braided core strand of 25 hemp, and transverse threads knitted onto said longitudinal braided core. 85

19 15. Hat braid comprising a plurality of 30 longitudinal, flat, ribbon-like braided strands of a relatively stiff material, united into a single unitary fabric by means of an exterior casing, including rows of knitted stitches, 90 uniting said braided strands into a unitary structure. 95

20 16. A millinery and trimming braid including a longitudinal braided core strand of 35 a relatively form-retaining material and transverse crinkled threads knitted onto said longitudinal braided core. 100

25 17. A millinery and trimming braid including a longitudinal braided core strand of 40 hemp, and transverse crinkled threads knitted onto said longitudinal braided core. 105

30 18. Hat braid comprising a plurality of 45 longitudinally extending flat, ribbon-like, 50 hemp strands united into a single unitary fabric structure by means of a series of non-interlacing rows of knitted chain stitches extending longitudinally along the edges of said hemp strands and weft threads on the face 55 and on the back of said hemp strands interlaced with the stitches of said series of rows of knitted chain stitches; some of said weft threads being relatively bulky and crinkled. 110

35 19. Hat braid comprising a plurality of 60 longitudinally extending flat, ribbon-like, 65 braided hemp strands knitted into a single unitary fabric structure by means of a series of non-interlacing rows of knitted chain 70 stitches extending longitudinally along the edges of said hemp strands and weft threads 75
